UNITED STATES PATENT OFFICE.

FREDERICK N. ROSS, OF PONTIAC, MICHIGAN, ASSIGNOR TO BUTTON ATTACHING MACHINE COMPANY, OF PONTIAC, MICHIGAN, A CORPORATION OF MICHIGAN.

TRIPLE-CUP BUTTON.

Application filed August 25, 1923. Serial No. 659,247.

To all whom it may concern:

Be it known that I, FREDERICK N. Ross, citizen of the United States, residing at Pontiac, in the county of Oakland and State 5 of Michigan, have invented certain new and useful Improvements in Triple-Cup Buttons, of which the following is a specification.

This invention relates to buttons and more 10 particularly concerns the interior construction.

At the present time the button most universally used on working men's clothes is provided with a paper slug that is inserted 15 between the front and back members of the button for the purpose of reinforcing the front. The front of the button is made of a very thin metal and unless this is reinforced in some manner it can be very easily 20 bent out of shape or dented.

The use of a paper slug possesses many disadvantages. It is liable to vary in thickness from .050 to .075. This variation although fairly small, is sufficient to prevent 25 the manufacturer of the buttons from using automatic machinery in their manufacture. Again, the paper is very sensitive to atmospheric changes and moisture in the atmosphere will tend to swell the slug so that it 30 is much thicker and will not fit in the button properly. Due to this defect much difficulty has been experienced in the past in assembling the button parts together. Furthermore, the working man desires to wash 35 his working clothes without having to remove the buttons therefrom. The water in which he washes his clothes will in time seep through the interior of the button, and has been known to cause the paper to swell to 40 such an extent as to force the front and back parts of the button apart. Quite often the button is forced out of shape before the same is sewed on to the clothes and these buttons must necessarily be scrapped.

There are many styles of buttons on the market some of which are provided with openings in the front part similar to the form of button shown in Figs. 3 and 4 of applicant's application. It is customary to 50 place a colored insert behind the front part of the button so that a color will show through the opening. The present method of manufacturing this style of button is to insert a small disk of tin that is enameled to 55 suit the color requirements, between the pa-

per slug and the front part of the button. This of course, increases the amount of handling which is at the present time done entirely by hand.

Applicant's construction is well adapted 60 to this style of button without necessitating any extra parts as is now the case. One of the main objects of applicant's invention is to provide a spacer that is sufficiently strong and uniform in size, that is capable of use 65 for either style button without any structural changes.

In the drawings:

Fig. 1 is a side elevation of the button.

Fig. 2 is a vertical sectional view of the 70 same.

Fig. 3 is a plan elevation of the open face button.

Fig. 4 is a vertical sectional view taken on the line 4—4 of Fig. 3. 75

Fig. 5 is a detail in perspective of the cup-shaped spacer.

The button is made up of a front member *a*, a back member *b* to which is secured a ring portion *c* adapted to pass through the 80 fabric and to have an anchoring member (not shown) secured thereon to retain the button in place on the fabric. This construction is standard.

As I said before, the front part of the 85 old style button is reinforced by a paper slug inserted between the front and back members. I provide a cup-shaped spacer or slug *d* which is adapted to be fitted between the front and back parts of the button the 90 bottom wall *e* of said spacer having a contour that will conform to the contour of the button front. It will be seen that when the front and back parts of the button are 95 clinched together, the bottom of said spacer will contact with the inner face of the button front, while the edge of said cup-shaped spacer will contact with the button back thereby thoroughly reinforcing the button front. 100

In Figs. 3 and 4 I show a style of button known as the open face button, which is provided with an opening *f* in the button front. To provide the proper background for the opening I color enamel the face of 105 the cup-shaped spacer designated *g* as shown in Fig. 4.

In this way I provide a metal spacer and reinforcing member which is adaptable to both styles of buttons shown in the draw- 110

ings. It is obvious that the metal spacer is not sensitive to atmospheric conditions and can be manufactured in production with a few thousandths of an inch variation in dimensions. This enables the manufacturer to make the button with the use of automatic machinery which of course would naturally increase the production and decrease the cost of the button. The metal cup-shaped spacer or slug is so uniform in size that there is no danger of clogging up an automatic machine which feeds them to the assembling mechanism.

Another advantage in using a triple cup button is that in a ring button as shown in the drawings, the turned over legs *h* take up considerable space within the interior of the button. The cup-shaped spacer thereby can contact with the front and back members of the button without contacting with these turned over legs. In using a paper slug as is done with the present day buttons, the paper slug will be dented in to allow for these turned over leg portions. Obviously this is not as nice a fit as when the cup-shaped metal slug is used.

I am aware of the fact that the prior art shows the use of three cup-shaped members but they do not function or obtain the same result as does applicant's triple cup-shaped button. Applicant's third cup acts as a spacer and reinforcing member for the two other cups. Besides, the third cup can be colored so as to provide the proper coloring background for an open face button without departing from the structural shape of the several cups.

What I claim is:

1. A button having in combination, a cup-shaped back member, a cup-shaped front member whose face is formed with a rounded contour, said front and back members telescoping together, and a cup-shaped metal slug arranged to be inserted between the said cup-shaped front and back members, the face of said cup-shaped slug having a contour complementary to the rounded face

of the front member and arranged to contact therewith for the purpose of reinforcing the same.

2. A button having in combination, a cup-shaped back member, a cup-shaped front member provided with an opening in the face thereof, and a cup-shaped slug bearing a colored surface and adapted to be fitted between said front and back members for the purpose of forming a colored background for the opening in the face of the button, and for reinforcing the same.

3. A button having in combination, a cup-shaped back member, a cup-shaped front member provided with an opening in the face thereof, and a cup-shaped metal reinforcing slug having the face colored so as to form a colored background for the opening in the front face of the button.

4. A triple cup button comprising two telescoping cup-shaped members, and a spacer cup inserted between the two telescoping cup members and clamped therebetween when the two telescoping cup shaped members are assembled together.

5. A button, having in combination a cup-shaped front and back member arranged to telescope together, and a cup-shaped slug inserted therebetween, the entire face of said slug contacting with one of said button members to reinforce the same and the back of the said slug contacting with the other button member, whereby the slug is clamped between the button members when they are assembled together.

6. A button, having in combination cup-shaped front and back members arranged to telescope together, and a cup-shaped metal spacer inserted therebetween, the face of said cup-shaped spacer contacting with the button front to reinforce the same, the back of said cup-shaped spacer contacting with the button back, whereby the spacer is clamped between the button front and button back when they are assembled together.

In testimony whereof I affix my signature.
FREDERICK N. ROSS.
